Inventor:

John W. Culmer,

By Chas. F. Benjamin,

Attorney.

UNITED STATES PATENT OFFICE.

JOHN W. CULMER, OF NEW BRIGHTON, PENNSYLVANIA.

DESIGN FOR A SCALE-WEIGHT.

SPECIFICATION forming part of Design No. 25,721, dated June 30, 1896.

Application filed October 10, 1895. Serial No. 565,293. Term of patent 3½ years.

To all whom it may concern:

Be it known that I, JOHN W. CULMER, a citizen of the United States, residing at New Brighton, in the county of Beaver and State of Pennsylvania, have invented and produced a new and original Design for Scale-Weights; and I do hereby declare the following to be a full, clear, and exact description of the same, reference being had to the accompanying drawings, forming a part thereof.

The leading feature of this design consists in a series of panels upon the reading-face of the weight, as shown.

In the drawings, Figure 1 is a top plan, 15 and Fig. 2 a vertical cross-section, of the design on the line $x-x$ of Fig. 1.

A is the weight; b, the edge thereof; c, a recess therein, and d a narrow concentric rim upon the face, within the edge.

20 B, C, and D are the panels forming the

characteristic feature of the design. Each panel shows a ground color distinct from that of either of the other two, as indicated, respectively, by the oblique, the vertical, and the horizontal lines within the panels in 25 the drawings.

No panel is confined in the design to a particular ground color, but appears of any color desired that differs from the colors of the two other panels.

30 I claim—

The new and original design for a scale-weight substantially as shown and described.

In testimony whereof I affix my signature in presence of two witnesses.

JOHN W. CULMER.

Witnesses:

W. C. GRIGSBY,

FRANK B. MARLOW.
